UNITED STATES PATENT OFFICE.

KARL A. SCHULTZ, OF CHICAGO, ILLINOIS.

PROJECTILE.

1,302,720.

Specification of Letters Patent.

Patented May 6, 1919.

Application filed April 3, 1918. Serial No. 226,361.

To all whom it may concern:

Be it known that I, KARL A. SCHULTZ, a citizen of the United States, residing at Chicago, in the county of Cook and State of Illinois, have invented certain new and useful Improvements in Projectiles, of which the following is a specification.

My invention relates to ordnance and has for its primary object the provision of an improved projectile and a gun especially adapted to discharge the same, the combined action of projectile and gun being such as to result in a reduction of air pressure against the flying projectile for a given amount of high explosive carried in the shell. A further object is the provision of a projectile which, in flight, shall have two gyrating parts opposed to each other and rotating about a common axis transverse to the line of flight, the result of this improved construction being a steadier trajectory.

Other objects and advantages of my invention will appear from the following description taken in conjunction with the accompanying drawings which form a part of this specification and illustrate the preferred embodiment of my invention.

In the drawings:

Figure 1 is a side elevation of the projectile of the present invention:

Fig. 2 is a section on line 2—2 of Fig. 1;

Fig. 3 is a side elevation of a modified form of projectile;

Fig. 4 is a section taken on line 4—4 of Fig. 3;

Fig. 5 is a view of the muzzle end of a gun adapted to discharge the projectile shown in Fig. 1, and illustrating in dotted lines certain rifling by means of which the projectile illustrated in Figs. 3 and 4 may be fired; and

Fig. 6 is a view taken on line 6—6 of Fig. 5 illustrating one half of the gun adapted for firing the projectile shown in Figs. 1 and 2, illustrating in dotted lines rifling suitable for firing the projectile illustrated in Figs. 3 and 4, and showing in diagram a fragment of a breech block for closing the breech of the gun.

Reference numeral 10 indicates the upper half and 11 the lower half of the preferred form of my improved projectile, these halves comprising each a hollow disk having one flat side 12 and one substantially spherical side 13 which is centrally flattened as at 14. The flat sides 12 of the two halves are placed

against each other and the halves are connected by common pivot pin 15 passing through alined central bearings in the disks.

The periphery of each disk is provided with gear teeth numbered 16 on the upper half 10 and 17 on the lower half 11.

The interior of each disk is preferably filled with a high explosive such as gun cotton or nitro-glycerin dynamite 18. When assembled the projectile, in edge view, presents the contour seen in Fig. 2, being substantially that of an ellipse having centrally flattened sides and pointed ends.

In end view the gun for firing this projectile presents the same general contour as that of the shell. This is seen in Fig. 5 where two substantially identical castings 19 and 20, provided with ears 21, are fastened together by bolts 22. On the interior of the casting 19 is formed a rack 23 along one edge, the teeth of this rack being adapted to mesh with the gear teeth 16 on half 10 of the projectile. A rack 24 similar in all respects but located on the opposite side of the gun, is formed on casting 20; the teeth of rack 24 meshing with gear teeth 17 on half 11 of the projectile. The breech 25 of the gun may be of any suitable form and any convenient type of breech block 26 may be employed to close it.

In the operation of the invention the projectile shown in Figs. 1 and 2 is positioned near the breech of the gun, the teeth 16 engaging rack 23 only and the teeth 17 engaging rack 24 only. By means of any suitable explosive positioned between the projectile and breech block the gun is fired. Inasmuch as the racks 23 and 24 are on opposite sides of the gun and each engages its respective half of the projectile it is obvious that the two halves 10 and 11 will whirl rapidly in opposite directions about pivot 15 during the flight of the shell.

It is to be noted, however, that the racks 23 and 24 may if desired be positioned on the same side of the gun, though on opposite castings. By such construction the two halves of the shell would rotate in a common direction. When these halves revolve in opposite directions the opposed gyroscopic effects act to steady the movement of the projectile during flight and to counteract to a large extent the action of the wind in causing it to deviate from its course. When the halves revolve in a common direction the shell's trajectory is curved in a

lateral direction, as the "curve" ball thrown by a baseball pitcher, so that the projectile can be literally thrown around a corner with reasonable accuracy. The gun is mounted so that when the projectile is fired the pivot pin 15 is substantially vertical or at least stands in an up and down position. Thus the whole face of the projectile is presented to the earth and the force of gravity tending 10 to pull the shell downward is resisted by air pressure against this large surface, resulting in providing a longer range for this projectile than that of the ordinary cylindrical pointed shell.

15 A modified form of projectile is illustrated in Figs. 3 and 4 wherein the gear teeth 16 and 17 are omitted and in their stead each half of the projectile is provided with a single round projection, 27 on half 28, and 29 on half 30; the halves 28 and 30 corresponding respectively to halves 10 and 11 in all other respects. These projections are shaped to fit within riflings formed in the gun. The modifications necessary in the 25 gun to enable it to fire the shell depicted in Figs. 3 and 4 are indicated in dotted lines in Figs. 5 and 6, where rifling 31 is shaped to receive projection 27 and rifling 32 to fit projection 29; in case these riflings are used, 30 the racks 23 and 24 are omitted from the interior of the gun. The use of the form of shell shown in Figs. 3 and 4 with the rifled gun provides a much slower speed of rotation in the two halves 28 and 30 than is the 35 case in the other form of projectile and gun wherein the gear teeth and racks are employed. The riflings may, as in the case of the racks, be so positioned as to cause both halves of the projectile to turn in a common direction without relative movement, thereby enabling the gunner to send a shell 40 in a wide curve and around an obstacle interposed between him and his target.

By altering the location of one of the 45 racks and the corresponding teeth, or by varying the location of one of the projections and its rifling in the gun the two halves of the projectile may be made to revolve in opposite directions or in the same direction 50 at different speeds relative to each other, so that the degree of curving horizontally in the shell's trajectory may be governed in the construction of the gun and shell: also the teeth or rifling on one casting of the gun 55 may be omitted altogether as well as the corresponding teeth or projection, whereby one half of the projectile will fly through the air without revolving at all while the other

half turns rapidly on pivot 15, thereby further modifying the path of the shell, and in 60 this latter arrangement the revolving half of the projectile may be made to turn in either direction to give the shell a definite deviation from a vertical plane passing through the gun. 65

While I have described my invention with more or less minuteness as being embodied in certain precise forms, yet it will be understood that I do not desire to limit myself thereto unduly or any more than is 70 pointed out in the appended claims. On the contrary I contemplate all proper changes in form, construction and arrangement, the omission of immaterial parts and the substitution of equivalents as circumstances 75 may suggest or necessity render expedient.

I claim:

1. A projectile comprising relatively movable parts, and means pivoting said parts together on an axis at right angles to 80 the trajectory of the projectile.

2. A projectile comprising concentric disks and means pivoting said disks together for relative movement on an axis at right angles to the trajectory of the projectile. 85

3. A projectile comprising concentric disks each chambered for carrying a mass of explosive, and a pivot centrally positioned in the disks and connecting them together for relative rotation. 90

4. A projectile comprising concentric disks, each disk having a flat face and a centrally flattened spherical face, said flat faces being contiguous, a pivot centrally positioned in the disks and connecting them together for relative rotation, and means formed on each disk for receiving a rotative impulse. 95

5. A projectile comprising concentric 100 disks, means pivoting the disks together for relative rotation, and an element on each disk adapted to receive a rotative impulse.

6. A projectile comprising concentric disks, means pivoting the disks together for 105 relative rotation, and gear teeth formed on each disk.

7. A projectile comprising concentric circular disks each having a flat face, said flat faces being contiguous, means centrally positioned in the disks and pivoting them together for relative rotation, and gear teeth peripherally positioned on each disk. 110

In testimony whereof I affix my signature.

KARL A. SCHULTZ.
